(57) **CLAIM**

We claim the design for a bottle, as shown.

DESCRIPTION

FIG. 1 is a front perspective view of a bottle embodying the new design;

FIG. 2 is a front elevational view of the bottle;

FIG. 3 is a rear elevational view of the bottle;

FIG. 4 is a right side elevational view of the bottle;

FIG. 5 is a left side elevational view of the bottle;

FIG. 6 is a top plan view of the bottle; and,

FIG. 7 is a bottom plan view of the bottle.
